UNITED STATES PATENT OFFICE.

FRANK LINDSAY, OF ETNA, PENNSYLVANIA.

WRENCH.

No. 878,968.

Specification of Letters Patent.

Patented Feb. 11, 1908.

Application filed August 1, 1907. Serial No. 386,592.

To all whom it may concern:

Be it known that I, FRANK LINDSAY, a citizen of the United States of America, residing at Etna, in the county of Allegheny and 5 State of Pennsylvania, have invented certain new and useful Improvements in Wrenches, of which the following is a specification, reference being had therein to the accompanying drawing.

10 This invention relates to wrenches, and its object is to provide a simple and inexpensive device of the character adapted to be readily adjusted.

The construction of the improvement will 15 be fully described hereinafter, in connection with the accompanying drawing, which forms a part of this specification, and its novel features will be defined in the appended claims.

In the drawing, Figure 1 is a side elevation 20 of a wrench embodying the invention, Fig. 2 is a transverse section on the line $x-x$ of Fig. 1 with the fixed jaw reversed, and Fig. 3 is a side elevation of the fixed jaw detached.

25 The reference numeral 1 designates a frame formed with threaded bearings 2 and 3 for the passage of a shank 4 which is flattened on opposite sides, and formed with threads 5, engaging the threads of a serrated nut 6, said 30 nut occupying the space between the bearings 2 and 3.

A handle 7 is secured to the lower end of 35 the frame 1, and adjacent to its upper end the frame is formed with two parallel laterally projecting integral arms 8, between which is detachably secured by a pin 9 the depending bracket 10 of the fixed jaw 11. This jaw 11 rests upon the arms 8 and is beveled on its upper surface 12 as shown.

40 The side of the frame is longitudinally recessed as at 13 to provide a shoulder 14 upon which the lower end of the bracket 10 rests. The upper end of the recessed portion 13, is cut away to form a rest or shoulder for the 45 inner edge of the fixed jaw 11, said jaw extending inwardly past the recessed portion 13. The upper end of the shank 4 carries the movable jaw 15 of the wrench, said jaw being preferably formed integral with the

shank and having its working face provided 50 with teeth or notches 16.

The operation of the wrench will be obvious from the illustration in Fig. 1, the turning of the serrated nut 6 serving to adjust the jaw 15 with relation to the fixed jaw 8. 55

A characteristic of the invention is, that the shank and jaw carried thereby, are adjustable, thus making the upper, or outermost jaw the movable member, instead of adjusting the lower jaw upon the shank as in 60 the ordinary type of wrench. The removability of the jaw 12 also adds to the utility of the device, permitting the removal of said jaw when worn, and the substitution of one 65 form of jaw for another.

Having now described my invention, what I claim as new, is—

In combination, a wrench frame having as a part thereof a body portion, a handle, and a pair of laterally extending arms formed integral with said body portion at a point removed from the top edge thereof thereby providing a vertically extending shoulder, said arms constituting a removable jaw support and suitably spaced apart to form a web 70 receiving opening and further having formed therebetween at the inner ends a vertically disposed recess forming a continuation of the web receiving opening and with the bottom wall of said recess constituting a ledge, a jaw 75 mounted upon said arms and abutting against said shoulder, a web formed integral with the jaw approximately centrally of its lower face and positioned within said opening and recess and mounted upon the ledge, 80 means extending through the arms of the web for connecting them together, a shank 85 mounted in said frame and carrying a rigid jaw arranged in suitable relation with respect to the movable jaw, and means for vertically adjusting the shank. 90

In testimony whereof I affix my signature in the presence of two witnesses.

FRANK LINDSAY.
